DESIGN FOR A HANDBAG

Ida Jolles, New York, N. Y.

Application February 9, 1944, Serial No. 112,523

Term of patent 7 years

(Cl. D87—3)

To all whom it may concern:

Be it known that I, Ida Jolles, a citizen of the United States of America, residing in New York city, county of New York, and State of New York, have invented a new, original, and ornamental Design for a Handbag, of which the following is a specification, reference being had to the accompanying drawing, forming part thereof, wherein the figure is a front perspective view of a handbag showing my new design.

The rear of the handbag is substantially the same in appearance as the front shown.

I claim:

The ornamental design for a handbag, substantially as shown and described.

IDA JOLLES.
